UNITED STATES PATENT OFFICE.

JOHN S. GOLDSMITH, OF NEW YORK, N. Y.

DESIGN FOR A PENDANT CHARM.

No. 87,516.

Specification for Design.

Patented Aug. 29, 1905.

Application filed June 29, 1905. Serial No. 267,668. Term of patent 14 years.

To all whom it may concern:

Be it known that I, JOHN SIDNEY GOLDSMITH, a citizen of the United States, residing at the borough of Manhattan, in the city, county, and State of New York, have invented a new, original, and ornamental Design for Fraternal Society Emblems, of which the following is a specification, reference being had to the accompanying drawing, forming part thereof.

The figure is a front elevation of a pendant charm, showing my design.

I claim—

The ornamental design for a pendant charm, as shown.

JOHN S. GOLDSMITH.
